UNITED STATES PATENT OFFICE.

SAMUEL M. KATZ, OF NEW YORK, N. Y.

DESIGN FOR A NAME PLATE FOR A DOOR.

Application filed January 10, 1924. Serial No. 8,289. Term of patent 14 years.

To all whom it may concern:

Be it known that I, SAMUEL M. KATZ, a citizen of the United States, residing in the city of New York, in the county of New York and State of New York, have invented a new, original, and ornamental Design for a Name Plate for a Door, of which the following is a specification, reference being had to the accompanying drawing, forming a part thereof.

In the drawing, the figure is a plan view of a name plate for a door showing my new design.

I claim:

The ornamental design for a name plate for a door, as shown.

SAMUEL M. KATZ.
